CONTAINER FOR PNEUMATIC CONVEYING SYSTEM

Anthony Philip Fischer, 1567 Kerr Ave.,
St. Lambert, Quebec, Canada

Filed May 21, 1971, Ser. No. 146,003

Term of patent 14 years

Int. Cl. D9—03

U.S. Cl. D9—216

FIG. 1 is a side elevational view of a container for a pneumatic conveying system showing my new design, the opposite side being substantially the same in appearance; and

FIG. 2 is an end elevational view thereof looking in the direction of the arrows 2—2 of FIG. 1, the opposite end being the same in appearance.

I claim:

The ornamental design for a container for pneumatic conveying system, as shown and described.
